UNITED STATES PATENT OFFICE.

FRANK PINK, OF PORTSMOUTH, ENGLAND.

SEPARATING LIQUIDS AND MEANS THEREFOR.

Application filed March 8, 1924, Serial No. 697,960, and in Great Britain June 9, 1923.

This invention relates to improvements in apparatus for separating liquids of different densities, such as oil and water, and is suited for use on board ship, or any floating support or on land.

An object of the present invention is to provide apparatus for separating liquids which is simple in construction, and by means of which a separation sufficient for practical purposes is obtained.

In the drawings accompanying this specification, Fig. 1 is an isometric view of a form of lay-out embodying a float valve control, Fig. 2 is a diagrammatic view of a 15 compartmented arrangement having a separate lead-out for each compartment, Fig. 3 a diagrammatic view of the invention applied to the double bottom of a ship, Fig. 4 is a section on the line A.B of Fig. 3 and Fig. 20 5 is a section on the line C.D of Fig. 3. Fig. 6 is a detail view of the valve gear, Fig. 7 an enlarged view of the separating chamber and inter-related parts, Fig. 8 is a plan view of Fig. 7 with the top cover removed, Fig. 25 9 is a view of a variant float arrangement, while Fig. 10 is a detail view of a control unit for the oil valve.

Referring to the drawings, there is provided a horizontally elongated closed chamber or tank 1, with a sloping top or roof (removed from Fig. 1). A collecting chamber 16 rises from the chamber 1. 2 is an inlet for the mixed liquid and 4 is a rising pipe or water discharge leg. Baffles are 30 provided in the tank 1. These baffles may be of various forms. 3 and 6 indicate the baffles. The baffles indicated by 6 are hinged to angle plates 7 and secured in position by bolts 8. 5 is a manhole. A relief pipe 49 for air may be provided at the 35 top of the oil chamber or dome, this pipe being taken up to a point above the water outlet.

14 is a discharge valve for the lighter liquid, and 15 the lighter liquid discharge pipe. As illustrated in Fig. 7 the pipe 15 may have its end upwardly bent so that the flow thereinto is a down flow. 13 is a float for controlling the opening and closing of said valve 14, said float sinking in the lighter liquid to open the valve and being floated by the heavier liquid to close the valve.

Means are provided for applying an increased force to actuate said discharge valve 14. One way comprises a piston valve 17 operated by the float 13.

On movement of the float in one direction the valve 17 admits steam or hydraulic pressure to one side of a piston in a cylinder 18 to move this to close the oil valve 14. As the ball moves in the other direction it operates to reverse the valve 17 and admits the pressure to the other side of the piston in the cylinder 18 to open the oil valve. Provision is made for exhaust of the spent motive agency.

The connections between the float and the piston valve 17 and also the connections between the cylinder 18 and the oil valve 14 may be by any convenient connecting devices.

The float 13 shewn is a cylinder float, like a carburettor float. This float is hollow and may be weighted, for example, with cement. The float 13 is mounted on a spindle 19 working between top and bottom 75 guides 20 and 21 respectively.

A lever arm 22 rests on the top of the float spindle 19 so that any movement of the float 13 is communicated to a spindle 23. The full outline at Fig. 7 shews the position of 80 the arm 22 when the float is up, and the dotted outline when the float is down.

One end of the spindle 23 is attached to a weighted arm 24, which arm or lever controls the operation of the piston valve 17 85 for operating the piston in the cylinder 18 for opening or closing the oil discharge valve 14.

There is provided a relief valve 25 in a pipe extension 26 for the removal of air 90 when the apparatus is first filled with water, and for the expulsion, when desired, of the last few gallons of oil after the float has closed the main delivery valve 14.

A steam coil 27, or a number thereof, may 95 be placed in the head or dome 16 to liquefy the oil, and enable the imprisoned air to easily escape from it, and also to allow any particles of water imprisoned, to more easily fall to the bottom. In the example shewn 100 by Fig. 7 two rings of the coil are designed to function as the top and bottom guides 20 and 21 for the float spindle 19. A thermostatic control for steam inlet is indicated at 28.

Fig. 9 shews a variant float control. In this arrangement there is a weighted rod 29. The rod 29 will not follow the float spindle 19 down to the bottom of its travel, the movable rod 29 being like the valve rod 110

of an internal combustion engine and the float spindle 19 like the tappet rod thereof. The rod 29 is under bias to return to its lowest position by a weight 30. By this arrangement in the event of slight movement being communicated to the float when it is at the lower part of its travel such movement will not be communicated to the valve operating gear, which otherwise may cause premature closing of the oil outlet valve. Fig. 9 shews a slide valve 31 and piston 32 for operating the oil valve 14.

An electrical control may be interposed between the float and a pressure device as for example the valves 17 or 31 for opening and closing the oil discharge valve.

Fig. 2 shews a lay out of tank or chamber 35 having separate compartments 36 formed by transverse partitions or baffles 11, extending to the top of the chamber. These baffles may be fixed or may be pivoted. Connecting the top of each compartment 36 to a main pipe 37 are branch pipes 38, and through these pipes 38 and the pipe 37 the oil passes from the tank 35 to the dome or collecting head 39. The head 39 has a suitable mechanical device or electrical device for controlling the delivery oil valve as previously described. A discharge valve 40 for emptying the chamber 35 is shewn in Fig. 2. This discharge valve may be fitted to the construction of Fig. 1.

Figs. 3, 4 and 5 shew the application of the apparatus according to the present invention to the double bottom of a ship of ten thousand tons.

In the example illustrated the separating chamber 41 is arranged in the cellular double bottom between girder plates 42 and 43 like the usual oil fuel and water ballast tanks. In some cases the usual transverse partition plates with manholes therein are used to form the baffles. Additional baffles 9 may be provided. A lining may, when necessary, be fitted in the separating chamber 41. The float chamber is indicated by 44. 45 is a bilge pump for delivering the mixture to the chamber 41. 46 is the water outlet or water leg and 47 is an oil conducting pipe, this pipe having branches 48 leading from the chamber 41.

Where I speak of flow in a substantially horizontal direction I would have it understood that the tank or pipe may have an inclined or undulating bottom so long as the direction is sufficiently near the horizontal to permit and maintain a surface separation of the two liquids during such flow.

The apparatus according to the present invention is such that as the mixture of oil and water passes through the tank, globules of oil rise continually to the top of the tank, being trapped by the baffles if these are present, and directed thereby to the top of each compartment between the baffles;

thereafter the oil gradually passes along directly or through a pipe line to the collecting head or receiver to be discharged.

Before passing into the separating chamber the mixture, for example, oily water may be passed through a filter to remove solid matter.

To operate the apparatus, the apparatus is first filled with water and as the water reaches the dotted line X—Z the float rises and closes the valve. Air is discharged through the relief valve 25 which is subsequently closed. The mixture of oil and water is then admitted, and the separator comes into action. The oil rises as described, and the water flows on and out of the rising pipe or water leg 4. As the water discharge level is above the discharge level of the oil outlet, there is always a working head or pressure at the oil outlet. As the oil collects in the head or dome it gradually displaces the water, and eventually when sufficient oil has collected, the float is no longer supported on water, and falls, opening the valve. The oil is then forced out through the valve. When the oil accumulates down to the level Y—Y, or if air accumulates, the float operates the oil outlet.

I would have it understood that by "separation" I do not necessarily mean complete separation, since with most liquids complete separation cannot be obtained by an apparatus of this type, but separation sufficient for practical purposes such as have been described. This apparatus is specially useful in cases where, as in the discharge of water which has been contaminated with oil, it is more important to get the heavier liquid approximately pure than to obtain the lighter liquid in such a condition. It thus enables bilge water to be discharged in harbour without infringing the law.

What I claim is:

1. Apparatus for separating liquids of different densities, comprising in combination, a horizontally elongated closed chamber, an inlet at one end of said chamber for the mixed liquid, an exit for the heavier liquid at the other end of said chamber, the mixed liquid having a substantially horizontal flow through the chamber from inlet to exit, means for creating a pressure on the mixed liquid in said chamber, a collecting chamber for the lighter liquid at the upper part of said closed chamber, an outlet in said collecting chamber through which the lighter liquid is expelled by reason of the pressure on the mixed liquid, a valve for said outlet, and a float for controlling the opening and closing of said valve, said float sinking in the lighter liquid to open the valve and being floated by the heavier liquid to close the valve.

2. Apparatus for separating liquids of different densities, comprising in combina-

tion, a horizontally elongated closed chamber, an inlet at one end of said chamber for the mixed liquid, an exit for the heavier liquid at the other end of said chamber, the mixed liquid having a substantially horizontal flow through the chamber from inlet to exit, means for creating a pressure on the mixed liquid in said chamber, baffles in said chamber, a collecting chamber for the lighter liquid at the upper part of said closed chamber, an outlet in said collecting chamber through which the lighter liquid is expelled by reason of the pressure on the mixed liquid, a valve for said outlet, and a float for controlling the opening and closing of said valve, said float sinking in the lighter liquid to open the valve and being floated by the heavier liquid to close the valve.

3. Apparatus for separating liquids of different densities, comprising in combination, a horizontally elongated closed chamber, a sloping top to said chamber, an inlet at one end of said chamber for the mixed liquid, an exit for the heavier liquid at the other end of said chamber, the mixed liquid having a substantially horizontal flow through the chamber from inlet to exit, means for creating a pressure on the mixed liquid in said chamber, a collecting chamber for the lighter liquid extending upwardly from the horizontally elongated main portion of said closed chamber and at the inlet end thereof, an outlet in said collecting chamber through which the lighter liquid is expelled by reason of the pressure on the mixed liquid, a valve for said outlet, and a float for controlling the opening and closing of said valve, said float sinking in the lighter liquid to open the valve and being floated by the heavier liquid to close the valve.

4. Apparatus for separating liquids of different densities, comprising in combination, a horizontally elongated closed chamber, an inlet at one end of said chamber for the mixed liquid, an exit for the heavier liquid at the other end of said chamber, the mixed liquid having a substantially horizontal flow through the chamber from inlet to exit, means for creating a pressure on the mixed liquid in said chamber, a collecting chamber for the lighter liquid at the upper part of said closed chamber, an outlet in said collecting chamber through which the lighter liquid is expelled by reason of the pressure on the mixed liquid, a valve for said outlet, a float for controlling the opening and closing of said valve, said float sinking in the lighter liquid to open the valve and being floated by the heavier liquid to close the valve, and means for applying an increased force to actuate said valve, said means being interposed between the said float and the said valve.

5. Apparatus for separating liquids of different densities, comprising in combi-

nation, a horizontally elongated closed chamber, an inlet at one end of said chamber for the mixed liquid, an exit for the heavier liquid at the other end of said chamber, the mixed liquid having a substantially horizontal flow through the chamber from inlet to exit, means for creating a pressure on the mixed liquid in said chamber, movable baffles in said chamber, a collecting chamber for the lighter liquid at the upper part of said closed chamber, an outlet in said collecting chamber through which the lighter liquid is expelled by reason of the pressure on the mixed liquid, a valve for said outlet and a float for controlling the opening and closing of said valve, said float sinking in the lighter liquid to open the valve and being floated by the heavier liquid to close the valve.

6. Apparatus for separating liquids of different densities, comprising in combination, a horizontally elongated closed chamber, an inlet at one end of said chamber for the mixed liquid, an exit for the heavier liquid at the other end of said chamber, the mixed liquid having a substantially horizontal flow through the chamber from inlet to exit, means for creating a pressure on the mixed liquid in said chamber, a collecting chamber for the lighter liquid at the upper part of said closed chamber, an outlet in said collecting chamber through which the lighter liquid is expelled by reason of the pressure on the mixed liquid, a valve for said outlet, an auxiliary valve device for controlling the opening and closing of said valve, and a float for operating said auxiliary valve device, said float sinking in the lighter liquid and being floated by the heavier liquid.

7. Apparatus for separating liquids of different densities, comprising in combination, a horizontally elongated closed chamber, an inlet at one end of said chamber for the mixed liquid, an exit for the heavier liquid at the other end of said chamber, the mixed liquid having a substantially horizontal flow through the chamber from inlet to exit, means for creating a pressure on the mixed liquid in said chamber, a collecting chamber for the lighter liquid extending upwardly from the horizontally elongated main part of said closed chamber, an outlet in said collecting chamber through which the lighter liquid is expelled by reason of the pressure on the mixed liquid, said outlet being at the highest point of said collecting chamber, a valve for said outlet, and a float for controlling the opening and closing of said valve, said float sinking in the lighter liquid to open the valve and being floated by the heavier liquid to close the valve.

8. Apparatus for separating liquids of different densities, comprising in combination, a horizontally elongated closed cham-

ber, a sloping top to said chamber, an inlet at one end of said chamber for the mixed liquid, an exit for the heavier liquid at the other end of said chamber, the mixed liquid 5 having a substantially horizontal flow through the chamber from inlet to exit, means for creating a pressure on the mixed liquid in said chamber, baffles in said chamber, a collecting chamber for the lighter liquid extending upwardly from the horizontally elongated main part of said closed chamber, an outlet in said collecting chamber through which the lighter liquid is expelled 10 by reason of the pressure on the mixed liquid, a valve for said outlet, and a float for controlling the opening and closing of said valve, said float sinking in the lighter liquid to open the valve and being floated by the heavier liquid to close the valve.

15 9. Apparatus for separating liquids of different densities, comprising in combination, a horizontally elongated closed chamber, a sloping top to said chamber, an inlet at one end of said chamber for the mixed

20 liquid, an exit for the heavier liquid at the other end of said chamber, the mixed liquid having a substantially horizontal flow through the chamber from inlet to exit, means for creating a pressure on the mixed liquid in said chamber, baffles in said chamber, a collecting chamber for the lighter liquid extending upwardly from the horizontally elongated main part of said closed chamber, an outlet in said collecting chamber through which the lighter liquid is expelled 25 by reason of the pressure on the mixed liquid, a valve for said outlet, a float for controlling the opening and closing of said valve, said float sinking in the lighter liquid to open the valve and being floated by the heavier liquid to close the valve, and means for applying an increased force to actuate said valve beyond that exerted by the float, said means being interposed between the said float and the said valve.
